UNITED STATES PATENT OFFICE.

OSCAR E. BREMER, OF DE KALB, ILLINOIS.

CORE-GRINDING MACHINE.

1,049,200.

Specification of Letters Patent. Patented Dec. 31, 1912.

Application filed May 16, 1912. Serial No. 697,662.

To all whom it may concern:

Be it known that I, OSCAR E. BREMER, a citizen of the United States, and a resident of the city of De Kalb, county of Dekalb, 5 and State of Illinois, have invented certain new and useful Improvements in Core-Grinding Machines, of which the following is a specification.

My invention relates to improvements in 10 core grinding machines and more specifically to a machine of this character which is adapted to taper the ends of cores and thereby render the same of greater utility in the molding processes of a foundry.

15 The object of my invention is to provide a core grinding machine of such a construction as to be capable of tapering cores with but a minimum of exertion on the part of the operator.

20 A further object of my invention is to provide a grinding machine of the character stated which shall be simple of construction and efficient in operation.

25 With these objects in view my invention consists in the combinations and arrangements of parts all as will be hereinafter described and claimed.

30 My invention will be best understood by reference to the accompanying drawings forming a part of this specification, and in which the figure is a perspective view showing a core grinding machine embodying my invention.

35 The preferred form of construction as illustrated in the accompanying drawing comprises a frame or pair of standards 1 which are rigidly secured to a suitable bench 2. The standards 1 are each provided with a pair of bearings 2' in which are journalized 40 shafts 3 and 4, the former being a high speed shaft and the latter a power shaft adapted to drive the high speed shaft. The shaft 3 is provided with a spur pinion 5 which meshes with a driving spur gear 6 carried by the shaft 4, the construction being obviously such that the shaft 3 will 45 rotate at a higher speed than the shaft 4. The latter shaft carries a pulley 7 at one end and a spur pinion 8 at the other, there being a spur gear 9 loosely mounted on the shaft 3 and driven at a low speed by means of the pinion 8 as clearly illustrated in the figure. Projecting laterally from one face 50 of the spur gear 9 and extending to adjacent one extremity of the shaft 3 is an arm 10 the free extremity of which is formed into

a bearing 11. A stub shaft 12, indicated by dotted lines, is journaled in the bearing 11 and disposed at an angle to the axis of the shaft 3. The stub shaft 12 is rotated at approximately the same speed as the shaft 3 by means of a bevel gear connection there-with comprising bevel gears 13 and 14. From this construction it is apparent that during the operation of the machine that the shaft 3 will rotate at a high speed and that the spur gear 9 and arm 10 carried thereby will revolve at a low speed, the stub shaft 11 rotating at approximately the same speed as the shaft 3. Secured to the end of the stub shaft 11 opposite the bevel gear connection thereof is a grinding disk or wheel 15, which is disposed at an acute angle to the axis of the shaft 3, said axis intersecting the grinding face of said wheel. Thus the grinding wheel 15 is adapted to not only rotate at a high speed on its own axis but to revolve bodily about the axis of the shaft 3, forming a planetary movement.

In order to form a taper 16 on a cylindri- 80 cal core 17 the latter is placed in a core support comprising a V-shaped holder 18 the sides of which extend horizontally. The holder 18 is so mounted that cores supported thereby may be arranged in axial alignment with the shaft 3 and thus effect the desired result when the same are pressed into contact with the grinding face of the wheel. In order to effect vertical adjustment of the core holder 18 which is necessary 85 where cores of varying diameter are ground, a slotted arm 19 is formed integral with said holder and adjustably secured to a standard 20 by means of a set screw 21. The full construction of the set screw 21 is not illustrated but the same will be readily understood by those skilled in the art.

In the operation of the machine a core 17 is placed in the holder 18 and brought into contact with the grinding surface of the 100 wheel 15 which thereupon begins to grind a taper on one end of the core, the length or size of the taper depending upon the time of contact and pressure between the grinding face and core. The operator merely 105 holds the core in the holder 18 and feeds the same longitudinally as the taper is being ground. Before grinding a core it is necessary to vertically adjust the holder 18 so that the axis of the core to be ground will 110 be in axial alignment with the shaft 3.

A core grinding machine as set forth may

be operated by any one unskilled in grinding cores since the mounting of the grinding wheel of the machine is such that a true taper is automatically formed. The machine is moreover simple of construction and highly efficient in operation.

While I have illustrated and described the preferred form of construction for carrying my invention into effect, this is capable of 10 variation and modification without departing from the spirit of the invention. I, therefore, do not wish to be limited to the precise details of construction set forth, but desire to avail myself of such variations and 15 modifications as come within the scope of the appended claims.

Having described my invention what I claim as new and desire to secure by Letters Patent is:

20 1. In a core grinding machine, a driving shaft; a driven shaft operatively connected to said driving shaft; a member journaled on said driven shaft and gear connected with said driving shaft to revolve more slowly than said driven shaft; an arm on 25 said member; a grinding wheel journaled in said arm and operatively connected with said driven shaft to be revolved on its axis thereby; and a core support adapted to support a core in axial alinement with said driven shaft, substantially as described.

2. In a core grinding machine, a bearing and a shaft journaled therein, a spur gear loosely mounted on said shaft and having an 30 arm projecting from one side thereof, the extremity of said arm being adjacent an extremity of said shaft and formed into a bearing, a shaft journaled in said last mentioned bearing and arranged in operative relation with said extremity of said shaft, the axes of said shafts being disposed at an angle to each other, a grinding wheel carried by the shaft journaled in the bearing of said arm, means for rotating said spur gear and 35 said first mentioned shaft, and a core support adapted to hold cylindrical cores in axial alinement with said first mentioned shaft and in contact with the grinding face of said wheel, substantially as described.

50 3. In a core grinding machine, the combi-

nation with a core support adapted to hold cylindrical cores, of a shaft disposed in axial alinement with a core on said support, means for driving said shaft at a high speed, a spur gear loosely mounted on said shaft, 55 means for driving said spur gear at a low speed, an arm rigidly connected with one face of said spur gear and projecting laterally therefrom to adjacent one end of said shaft, there being a bearing formed in the free extremity of said arm, a stub shaft journaled in said bearing and arranged in operative relation with said first mentioned shaft, and a grinding wheel carried by said stub shaft and adapted to revolve therewith 60 about the axis of said first mentioned shaft, the disposition of said core support being such that a core mounted thereon may be placed in operative relation with the grinding face of said wheel, substantially as described.

4. In a core grinding machine, a frame and a pair of parallel shafts journaled therein, one of said shafts being a power shaft and the other a high speed shaft geared to 75 the power shaft, a spur gear loosely mounted on said high speed shaft, a spur pinion carried by said power shaft meshing with said spur gear, an arm projecting laterally from said spur gear having a bearing at the free 80 extremity thereof, the disposition of said bearing being spaced apart from the axis of said second shaft and adapted to revolve thereabout, a stub shaft journaled in said bearing and arranged in bevel gear connection with said second shaft, a grinding wheel carried by said stub shaft the grinding face thereof intersecting the axis of said second shaft, and a vertically adjustable core support adapted to hold cylindrical cores in 85 contact with the grinding face of said wheel and in substantial alinement with said second shaft, substantially as described.

In testimony whereof I have signed my name to this specification in the presence of 90 two subscribing witnesses.

OSCAR E. BREMER.
